DESIGN FOR A COMBINED INSECTICIDE CONTAINER AND EJECTOR

Bereniece Nance Forrest and Harry D. Bell, New York, N. Y., assignors to Mysterious Chemical Co. Inc., New York, N. Y., a corporation of New York

Application August 8, 1939, Serial No. 86,534

Term of patent 14 years

To all whom it may concern:

Be it known that we, Bereniece Nance Forrest and Harry D. Bell, citizens of the United States of America, and residents of New York, county of New York, and State of New York, have invented a new, original, and ornamental Design for a combined Insecticide Container and Ejector, of which the following is a specification, reference being had to the accompanying drawing, forming part thereof.

In the drawing:

Figure 1 is a front elevational view of a com-

bined insecticide container and ejector showing our new design.

Figure 2 is a side elevation thereof.

Figure 3 is a top plan view of Figure 1.

Figure 4 is a sectional view taken on line 4—4 of Figure 1.

We claim:

The ornamental design for a combined insecticide container and ejector, substantially as shown.

BERENIECE NANCE FORREST.
